UNITED STATES PATENT OFFICE

166,663

PETTICOAT

Anna Friedman, New York, N. Y.

Application September 6, 1951, Serial No. 16,538

Term of patent 7 years

(Cl. D3—26)

To all whom it may concern:

Be it known that I, Anna Friedman, a citizen of the United States, residing in New York city, in the county of New York and State of New York, have invented a new, original, and ornamental Design for a Petticoat, of which the following is a specification, reference being had to the accompanying drawing, forming part thereof.

Fig. 1 is a front view of a petticoat showing my new design.

Fig. 2 is a fragmentary view of the petticoat shown in Fig. 1 with the outer half of the Shirred double ruffe in a raised position, showing the untrimmed inner faces being in juxtaposition, with the banded outer faces in a back to back relationship.

The rear of the petticoat is like the front.

The characteristic feature of my design resides in the double ruffle on the hem of the garment as shown.

I claim:

The ornamental design for a petticoat, substantially as shown and described.

ANNA FRIEDMAN.
